US00D716677S

(12) **United States Design Patent**
Messier et al.

(10) **Patent No.:** **US D716,677 S**
(45) **Date of Patent:** **** Nov. 4, 2014**

(54) **WEARABLE LOCATOR**

(71) Applicant: **iLOC Technologies Inc.**, Pointe-Claire (CA)

(72) Inventors: **Yves Messier**, Pierrefonds (CA); **Tony Fama**, Kirkland (CA); **Brian Miller**, Kirkland, CA (US); **Alain Martel**, Montreal (CA); **Daniel Tassé**, Montreal (CA)

(73) Assignee: **iLOC Technologies Inc.**, Pointe-Claire, Quebec (CA)

(**) Term: **14 Years**

(21) Appl. No.: **29/458,252**

(22) Filed: **Jun. 18, 2013**

(51) LOC (10) Cl. **10-04**

(52) U.S. Cl.

USPC **D10/98**; D10/70

(57) **CLAIM**

The ornamental design for a wearable locator, as shown and described.

DESCRIPTION

FIG. 1 is a top plan view of display portion of the wearable locator;

FIG. 2 is a bottom plan view of display portion of the wearable locator;

FIG. 3 is a left side plan view of the wearable locator;

FIG. 4 is a right side plan view of the wearable locator;

FIG. 5 is a back side perspective view of the wearable locator; and,

FIG. 6 is a front side plan view of the wearable locator.

1 Claim, 6 Drawing Sheets
